CUTTING MECHANISM FOR BREAD WRAPPING MACHINES

William Hoppe and Norman W. Lyon, Springfield, Mass., assignors to National Bread Wrapping Machine Co., Springfield, Mass., a corporation of Massachusetts

Application November 23, 1932, Serial No. 644,066

13 Claims. (Cl. 164—43)

This invention relates to cutting mechanism particularly adapted for the web supply of a wrapping machine such as is used for enveloping bread.

5 One object of the invention is to provide a cutting mechanism having a great rapidity of cut so that it may be employed in cutting a web in motion without the necessity of causing travel of the cutting mechanism in the direction of motion 10 of the web. Another object is to provide a cutting mechanism which will operate upon the free end of a web without the necessity of maintaining the web under tension or of carrying it upon a continuous support. Another object is to provide an improved cam mechanism for operating such a cutting device which will operate with great rapidity without causing a substantial amount of shock at the end of the cutting stroke. Additional objects will appear from the following description 15 and claims.

Referring to the drawing:

Fig. 1 is a side elevation, partly in section, of a cutting mechanism embodying the invention;

Fig. 2 is a smaller view showing the parts in a 25 different position of operation;

Fig. 3 is a top plan view of a portion of the mechanism shown in Fig. 1; and

Fig. 4 is a section on line 4—4 of Fig. 3.

The mechanism is shown as being supported 30 upon a frame 10 held together with suitable tie bars 11. Cutter bearing arms 12 and 13 are journaled upon a shaft 14 running transversely of the direction of travel of the web to be severed, as will appear more clearly below. This shaft is 35 preferably fixed to one of the members, the other being mounted for free rotation upon it. These arms 12 and 13 are shown as having the same axis, but if desired they could obviously be provided with separate supports which would not 40 necessarily be in exact axial alignment. The arm 12 carries near its end a cutter blade 15, while the arm 13 carries a block 16 and an end piece 17 spaced apart so as to form between them a slot 45 into which the cutter 15 may pass. These cutters are oscillated from the position of Fig. 1 to that of Fig. 2 by the mechanism to be described below, the two cutters meeting at substantially the plane of the paper web *w*. By reason of the provision of the double members 16 and 17 on the 50 arm 13, a support is given to the web throughout its width, this support being sufficient to enable the web to be severed without the necessity of maintaining it under tension.

The arm 12 is pivoted at 18 to a link 19. This 55 link is in turn pivoted at 20 to an arm 21 swing-

ing freely upon a supporting shaft 22 mounted upon the frame. The arm 13 has a rearward extension to which is pivoted at 23 a link 24, also coupled to the pivot 20. Upon the arm 21 is mounted a cam roll 25 held against the surface of a cam 26 by a tension spring 27 stretched between the arm 21 and a pin on the frame. The cam 26 is mounted upon a shaft 28 and is rotated continuously by any suitable mechanism. Upon the shaft is a sleeve 29 carrying a pivot 30 having its 10 axis eccentric to the axis of the shaft 28. A curved link 31 joins this pivot with the supporting shaft of the roll 25. As the cam revolves, the roll 25 will drop off the shoulder 50, forcing the pivot 30 downwardly as viewed in Fig. 1. As the 15 pivot moves downwardly it is carried underneath the shaft 28 by the necessary rotating movement of the sleeve 29, and as it swings underneath the shaft the sleeve acts like a crank approaching dead center, bringing the link 31 and consequently the roll 25 and its attached parts to rest without jar and with a smoothly decelerated movement.

By the mechanism described the closing movement of the cutting members will be started with 25 fair rapidity and will be terminated with a smoothness not found in the customary drop-off cam mechanism. It is an additional feature of the present invention that the normal speed of acceleration of the drop-off cam is increased, 30 this being possible without subjecting the mechanism to undue strain on account of the smooth deceleration due to the pivot 30. It is a recognized difficulty with drop-off cam mechanisms that where a cam roll is used to avoid friction 35 the speed of drop-off is greatly reduced on account of the fact that the roll rolls over the edge of the drop-off shoulder and does not drop sharply over it. To avoid this defect in the present case, a block 34 is mounted upon the arm 21 in 40 a position so that it normally does not make contact with the surface of the cam 26, being held just away from its surface by the roll 25. As the roll 25 passes over the shoulder 50, however, the block 34 is brought to rest upon the cam surface 45 allowing the roller to pass off the shoulder without producing any substantial movement of the arm 21. No movement of this arm other than the slight one necessary to bring the block 34 into contact with the cam surface occurs until 50 the block itself passes over the shoulder. Since the block and the shoulder can both be made with straight sides, the shoulder being even undercut if desired, the block is freed substantially instantaneously. The speed of acceleration toward the 55

axis of the cam may be made as high as desired by increasing the strength of the spring 27.

The web *w* is drawn over the stationary paper support 35 and under the guide 36 which is carried upon arms 37. These arms are pivoted upon a transverse shaft 38 carried upon the ends of arms 39 which in turn swing upon a stationary pivot shaft 40. The guide arms 37 have rearward extensions 41 connected by a stop rod 42 adapted to determine the lowermost position of the guide 36 by its contact with the undersides of arms 39. The guide 36 can, however, be raised manually if desired to assist in threading the paper. Running in gaps in the paper support are a plurality 10 of free rolls 43 above which are rubber rolls 44 carried upon the shaft 38, previously referred to. The web is in this case intended to be drawn out by a series of grippers upon a chain indicated at 45, the rolls 43 and 44 acting merely to hold the 20 leading end of the web in position after severance. In order to grip the web tightly upon severance the rubber rolls 44 are clamped by stopping the rotation of shaft 38. To do this a grooved roll 46 is mounted upon its shaft in position to be 25 contacted with by a grooved pad 47 carried upon an arm 48 swinging freely upon the transverse shaft 40. An extension 49 of this arm lies above a cam 50 carried by the shaft 14 and oscillated by this shaft as it turns with one of the cutting 30 members.

The operation of the device will now be considered. Although the particular form of web feeding mechanism is not of importance it may be assumed that the web *w* is being drawn out by a 35 continuously moving gripper upon the chain 45. While the web is traveling the roll 25 approaches the shoulder 50 and in passing over its edge lowers the block 34 against the cam surface. The slight movement of the cutters involved in this 40 action is without significance. When the block 34 passes over the shoulder 50 the spring 27 causes a rapid movement of the cam follower towards the axis of the cam, accelerating the cutting members very rapidly toward the closed position shown 45 in Fig. 2. As they approach the moving web they are moving with sufficient rapidity to form a clean cut completely across the web, allowing the severed sheet to continue its movement with the grippers and removing the tractive force of the 50 grippers from any influence upon the body of the web. At the same time the clamp 46-47 operates to hold the leading end of the web body firmly in position. In spite of the great rapidity with which the cutting members are closed, they 55 are decelerated with equal rapidity and without shock by the passage of the pivot 30 underneath the shaft 28. Due to this construction, a much stronger spring 27 and a much sharper drop-off of the cam can be used than with a construction 60 in which the closing movement of the cutters were to be interrupted merely by contact of the cam follower with the reduced portion of the cam. In the present case the portion of the cam below the shoulder is preferably cut away so that neither 65 the roll 25 nor the block 34 strike it,—the entire burden of stopping the movement of the cam follower being borne by the pivot 30. The pivot 30 is thus left in a dead center position and it is preferable to provide mechanism for at least initiating its return to the position of Fig. 1. In the present case this is done by a pin 32 on the cam 26, positioned to contact with a slanting abutment 33 on the link 31. Contact between these 70 members moves the pivot 30 to the left in Fig. 2 and positions the parts so that the follower may

be raised to its normal position by coaction between the cam surface and the roll 25.

What we claim is:

1. Web severing devices comprising a pair of cutter members pivoted upon substantially coincident axes extending across the web, one of the members having spaced portions forming a slot between them into which the other member is adapted to pass, and means for oscillating the cutter members simultaneously in opposite directions upon paths intersecting the line of travel of the web at substantially right angles, so that the cutting edge of one member passes into the slot in the other at the plane of the web and with a motion substantially normal thereto. 15

2. A cam mechanism for web severing mechanism and the like, comprising a drop off cam, a cam follower riding on the cam, a pivot mounted for rotation about an axis substantially coincident with the axis of the cam, and a link connecting the cam follower with the pivot to control the motion of the follower upon its release by the cam. 20

3. A cam mechanism for web severing mechanism and the like, comprising a drop off cam, 25 a cam follower riding on the cam, a spring drawing the cam follower towards the cam to impart a quickly accelerated motion to the follower upon its release by the cam, a pivot mounted for rotation about an axis substantially coincident 30 with the axis of the cam, and a link connecting the cam follower with the pivot to control the motion of the follower upon its release by the cam and to bring it to rest with a smooth deceleration. 35

4. A cam mechanism for web severing mechanism and the like, comprising a drop off cam, a cam follower riding on the cam, a spring drawing the cam follower towards the cam to impart a quickly accelerated motion to the follower upon its release by the cam, a shaft carrying the cam, a member mounted for free rotation upon the shaft, a pivot carried upon the member eccentric with respect to the shaft, and a link connecting the pivot to the follower, the parts being 45 so proportioned that upon the release of the follower by the cam the line joining the pivot and the shaft is at a substantial angle to the line joining the pivot with the follower, the pivot swinging around to the side of the shaft remote from the follower and opposing a progressively increasing resistance to the motion of the follower whereby the follower is decelerated smoothly and is brought to rest without shock. 50

5. A cam mechanism for web severing mechanism and the like, comprising a rotatable drop off cam, a cam follower comprising a roll and a bar trailing behind the roll and adapted to bear against the cam only when the roll starts over the drop off shoulder and to drop with great 60 suddenness over the shoulder when the shoulder has completely passed the roll. 55

6. A cam mechanism for web severing mechanism and the like, comprising a rotatable drop off cam, a cam follower comprising a roll and a block trailing behind the roll and adapted to bear against the cam only when the roll starts over the drop off shoulder and to drop with great 65 suddenness over the shoulder when the shoulder has completely passed the roll, a pivot mounted for rotation about an axis substantially coincident with the axis of the cam, and a link connecting the cam follower with the pivot to control the motion of the follower upon its release by the cam. 70

7. A cam mechanism for web severing mechanism and the like, comprising a rotatable drop off cam, a cam follower comprising a roll and a block trailing behind the roll and adapted to bear against the cam only when the roll starts over the drop off shoulder and to drop with great suddenness over the shoulder when the shoulder has completely passed the roll, a spring drawing the cam follower towards the cam, a rotatable shaft carrying the cam, a sleeve mounted for free rotation upon the shaft, a pivot carried upon the sleeve eccentric with respect to the shaft, and a link connecting the pivot to the follower, the parts being so proportioned that upon the passage of the block over the shoulder the line joining the pivot and the shaft is at a substantial angle to the line joining the pivot with the follower, the pivot swinging around to the side of the shaft remote from the follower and opposing a progressively increasing resistance to the motion of the follower whereby the follower is decelerated smoothly and is brought to rest without shock.

8. Web severing mechanism comprising a pair of cutter members pivoted upon axes extending across the web, a rotatable drop off cam, a cam follower riding on the cam, links connecting the cam follower with the cutter members at points respectively on opposite sides of their pivots, a pivot mounted for rotation about an axis substantially coincident with the axis of the cam, a link connecting the cam follower with the pivot to control the motion of the follower upon its release by the cam, and a spring drawing the follower towards the cam, the parts being so proportioned that upon the passage of the follower over the shoulder of the cam the line joining the last-named pivot and the cam shaft is at a substantial angle to the line joining said pivot with the follower, the pivot swinging around to the side of the shaft remote from the follower, whereby said cutting members will be accelerated rapidly from their separated positions towards a position in which their cutting edges pass at the plane of the web, and will be decelerated smoothly and stopped in that position without shock.

9. Web severing mechanism comprising a pair of cutter members extending across the web, a rotatable drop off cam, a cam follower comprising a roll and a block trailing behind the roll and adapted to bear against the cam only when the roll starts over the drop off shoulder of the cam and to drop with great suddenness over the shoulder when the shoulder has completely passed the roll, links connecting the cam follower with the cutter members at points respectively on opposite sides of their pivots, a shaft carrying the cam, a member rotatable upon the shaft and bearing a pivot eccentric with respect to the shaft, a link connecting the cam follower with the last-named pivot, and a spring drawing the cam follower towards the cam, the parts being so proportioned that upon the passage of the block over the shoulder of the cam the line joining the last-named pivot and the cam shaft is at a substantial angle to the line joining said pivot with the follower, whereby no substantial resistance is offered to the rapid acceleration by the spring of the follower and its connected parts to close the cutting members with great rapidity, the pivot swinging around to the side of the shaft remote from the follower, whereby the cutting members will be decelerating

smoothly and brought to rest without shock with their cutting edges passing at the plane of the web.

10. A cam mechanism for web severing mechanism and the like comprising a rotatable drop off cam, a follower riding on the cam, a spring drawing the cam follower towards the cam to impart a quickly accelerated motion to the follower upon its release by the cam, a shaft carrying the cam, a member carried upon the shaft eccentric with respect to the shaft, a link connecting the pivot to the follower, the parts being so proportioned that upon the release of the follower by the cam the line joining the pivot and the shaft is at a substantial angle to the line joining the pivot with the follower, whereby no substantial resistance is offered to the rapid acceleration of the follower by the spring, the pivot swinging around to the side of the shaft remote from the follower whereby the follower will be decelerated smoothly and brought to rest without shock, and means for initiating the return of the pivot back to its original position.

11. A cam mechanism for web severing mechanism and the like comprising a rotatable drop off cam, a follower riding on the cam, a spring drawing the cam follower towards the cam to impart a quickly accelerated motion to the follower upon its release by the cam, a shaft carrying the cam, a member carried upon the shaft eccentric with respect to the shaft, a link connecting the pivot to the follower, the parts being so proportioned that upon the release of the follower by the cam the line joining the pivot and the shaft is at a substantial angle to the line joining the pivot with the follower, whereby no substantial resistance is offered to the rapid acceleration of the follower by the spring, the pivot swinging around to the side of the shaft remote from the follower whereby the follower will be decelerated smoothly and brought to rest without shock, and a pin on the cam, and a slanting abutment on the link acted on by the pin to initiate the return of the pivot back to its original position.

12. Mechanism for severing a moving web comprising a pair of cutting members movable towards each other from opposite sides of the web, a spring urging the members together, means operative to release said members at a definite point in the cycle for free acceleration towards each other under the force of the spring, and positive means for decelerating the members with a substantially harmonic motion so that they are brought rapidly but smoothly to rest at a predetermined position.

13. Operating mechanism for web severing mechanism of the type in which the severing mechanism is given its web severing motion by a spring, comprising a quick release device for permitting the spring to accelerate the severing mechanism, and a rigid linkage connected to the severing mechanism and having its parts proportioned and arranged to permit substantially free movement of the severing mechanism by the spring at the instant of release and to decelerate the severing mechanism positively and rapidly and with a substantially harmonic motion so that it is brought smoothly to rest at a position predetermined by said linkage.
